UNITED STATES PATENT OFFICE.

MARSHALL J. HUGHES, OF JERSEY CITY, NEW JERSEY.

COMBINED PRINTING-PRESS AND STEREOTYPE CASTING-BOX.

SPECIFICATION forming part of Letters Patent No. 253,386, dated February 7, 1882.

Application filed September 19, 1881. (No model.)

To all whom it may concern:

Be it known that I, MARSHALL J. HUGHES, of Jersey City, Hudson county, New Jersey, have invented a new and Improved Combined 5 Printing-Press and Stereotype Casting-Box, of which the following is a specification.

Ordinarily in stereotyping, the mold or impression is taken and dried on a steam table or heater specially constructed and used for that 10 purpose alone. It is then placed in a casting-box specially constructed for that work. These appliances are costly and occupy no little space.

The object of my invention is to dispense with these separate appliances by utilizing 15 printing-presses in the work of stereotyping and production of plates and type-high casts; to which end the invention consists in the combination, with the bed and platen of a press, of the devices as hereinafter described and 20 claimed.

Reference is to be had to the accompanying drawings, forming part of this specification, in which similar letters of reference indicate corresponding parts in all the figures.

25 In the drawings, Figure 1 is a sectional side elevation of the essential parts of a press with my improvements applied, and Fig. 2 is a plan view of the platen.

30 A is the fixed bed of the press, and B the swinging platen, which may be fitted for movement by a treadle or lever in any usual manner. On the platen B is a gage, a, attached by screws or other suitable devices. This gage serves as a rest or support for the side bars 35 forming the casting-frame, and also forms the bottom of the casting-box.

b b are type-high bars or casting-gages, attached to platen B by the slotted arms e and screws d, which permit adjustment of the bars 40 to and from each other, according to the width of mold.

The gages a b may be of any suitable character. I do not limit myself in that respect, the object being that when the platen and bed are brought together a casting-box is formed, as shown in dotted lines. The said gages are necessarily adapted for convenient detachment to allow use of the platen for its ordinary function.

45 50 The matrix shown at f is secured by its edges

beneath the gages b, so that when the platen is brought up to form the box a cast is secured by pouring the molten metal in at the upper side.

The platen B, as shown in Fig. 1, is formed 55 hollow, and a tube, e, is connected therewith for supply of steam or hot water to heat the platen. This is for the purpose of drying the matrix, and takes the place of the usual steam-table or drying-box. It is also useful in connection with printing for warming the forms, 60 types or plates, and rollers in cold weather, so that they shall work freely, and to secure proper distribution of the ink.

In using the bed and platen for stereotyping, 65 the rollers and other parts of the press not required may be removed. This combination saves the expense of separate stereotyping apparatus and the space occupied by such apparatus. The required changes in the press can 70 be made in a moment and any ordinary press utilized.

Gas may also be used to heat the platen for drying the matrix, the burners being either fixed or movable.

75 I am aware that a hollow "flexible" platen has been used in a lithographic press, and that a heating appliance has been employed in connection with an apparatus for backing electro-type-shells. These features I disclaim.

Having thus described my invention, I claim as new and desire to secure by Letters Patent—

1. In combination with the bed of a printing-press, the hollow platen B, provided with a steam-pipe, d, and removable bars or gages 80 suitably arranged on its face for securing the stereotype-matrix and forming the sides of a stereotype casting-box, as shown and described.

2. In combination with the bed A of a printing-press, a platen, B, provided on its face with removable gages or bars, for the purpose specified, and with a heating appliance, whereby said bed and platen are adapted for use in forming stereotype-casts and drying-matrices 85 for the same, as specified.

M. J. HUGHES.
